(57) **CLAIM**

We claim, the ornamental design for a confection, as shown and described.

DESCRIPTION

FIG. 1 is a perspective view of a confection, showing our new design in an exemplary embodiment;

FIG. 2 is a top view of the embodiment shown in FIG. 1; FIG. 3 is a bottom view of the embodiment shown in FIG. 1;

FIG. 4 is a side view of the embodiment shown in FIG. 1; FIG. 5 is another side view of the embodiment shown in FIG. 1;

FIG. 6 is a front view of the embodiment shown in FIG. 1; FIG. 7 is a rear view of the embodiment shown in FIG. 1; FIG. 8 is a perspective view of a confection, showing our new design in another exemplary embodiment;

FIG. 9 is a top view of the embodiment shown in FIG. 8; FIG. 10 is a bottom view of the embodiment shown in FIG. 8;

FIG. 11 is a side view of the embodiment shown in FIG. 8; FIG. 12 is another side view of the embodiment shown in FIG. 8;

FIG. 13 is a front view of the embodiment shown in FIG. 8; and,

FIG. 14 is a rear view of the embodiment shown in FIG. 8. The break lines shown in the middle portion of the confection in FIGS. 8–12 indicate that the appearance of any portion of the article between the break lines forms no part of the claimed design.
